UNITED STATES PATENT OFFICE.

ALEXANDER B. SHERWOOD, OF CHICAGO, ILLINOIS, ASSIGNOR TO THE FUCHS & LANG MANUFACTURING COMPANY, OF NEW YORK, N. Y., A CORPORATION OF NEW YORK.

MACHINE FOR DAMPENING SHEETS.

No. 801,552.

Specification of Letters Patent.

Patented Oct. 10, 1905.

Application filed May 25, 1904. Serial No. 209,779.

To all whom it may concern:

Be it known that I, ALEXANDER B. SHERWOOD, a citizen of the United States, residing in Chicago, in the county of Cook and State 5 of Illinois, have invented certain new and useful Improvements in Machines for Dampening Sheets, of which the following is a specification.

The sheets of paper heretofore employed in 10 lithographing or printing commercial work were passed bodily through a fountain containing water, after which the surplus moisture had to be removed therefrom by drying. This method has been found to moisten the 15 sheets to too great an extent, prevents the uniform dampening of the same, and necessitates the dry pressing of the wavy sheets in order to flatten them out after printing.

The object of this invention is to supply to 20 lithographers, printers, and others a machine for dampening the sheets of paper in a uniform and reliable manner with a degree of moisture sufficient for bringing them into the best possible condition for printing and permitting the direct use of the sheets after they 25 have been dampened without requiring the removal of any surplus moisture from the same.

For this purpose the invention consists in the novel features and combinations of parts, 30 which will be fully described hereinafter and finally pointed out in the claims.

In the accompanying drawings, illustrative of one embodiment of the invention, Figure 1 is a side elevation of my improved machine 35 for dampening sheets. Fig. 2 is a vertical transverse section of the same, taken on line 2 2, Fig. 1. Figs. 3 and 4 are respectively a side elevation of the dampening mechanism, drawn on a larger scale, and a vertical longitudinal section of the same; and Fig. 5 is an 40 enlarged detail elevation showing one of the scrapers which engage the end portions only of the transmitting-roll.

Similar letters of reference indicate corresponding parts.

Referring to the drawings, A indicates the main frame of my improved machine for dampening sheets. To the upper part of the main frame is attached an auxiliary frame A', 50 provided at both sides with standards A², that are located vertically over the middle portion of the main frame, and end standards a³, which are connected by slightly-inclined portions a³

with the standards A², so as to support the table from which the sheets to be moistened 55 are fed to the machine. It is obvious, however, that the frame may be made in one integral structure. The table B is composed of a stationary section b and two folding sections b' b², the section b² being connected by 60 a hinge-joint b¹ at its under side with the section b' and the section b' by an upper hinge-joint b⁵ with the stationary section b, so that the sections may be folded up for shipment or when not required for use. To the end of 65 the section b² is applied a sheet-metal plate b³, which is countersunk into the section and extends beyond the same into proximity with the contact-point of two dampening-rolls C C'.

The shaft of the upper dampening-roll C is 70 supported in journal-bearings b⁶, adjustable by means of screw-spindles K, helical springs being interposed between the bearings and the upper end of the standards A², as shown in Fig. 3, while the shaft of the lower dampening-roll C' is supported in stationary bearings b¹⁰ of the standards A². Below the lower dampening-roll C' is arranged a moisture-transmitting roll C², journaled in adjustable bearings b¹² and rotated in contact with two 80 moisture-supplying rolls D, the shafts of which are supported in suitable bearings d, carried by horizontal yokes D', which are attached at their middle portion to the upright standards A², as shown in Figs. 2 and 3, the 85 bearings of said moisture-supplying rolls being capable of adjustment by means of set-screws d', engaging sockets on said bearings, so as to adjust the pressure of the moisture-supplying rolls D on the intermediate transmitting-roll D², as required for the proper transmission of the moisture from a fountain F, which is supported between the standards A² on a bottom board F', resting on supporting shoulders or ledges f of the standards A², as shown 90 clearly in Figs. 2 and 4.

The journal-bearings of the shaft of the transmitting-roll C² are adjustable by means of screw-spindles X, so as to be set higher or lower in the standards A² and in proper contact with the lower dampening-roll C'.

At the end of the main frame A opposite to the supporting-frame A' are arranged upright standards A³, which are about equal in height to the inner end of the feed-table B. 105 The standards A³ serve for supporting the

guide-rollers g , over which tapes or strings G are stretched, said tapes or strings G passing over the dampening-rolls $C C'$ and the guide-rollers g , the latter being of smaller diameter than the dampening-rolls, so that bights between the tapes or strings G gradually decrease in size as they pass away from the dampening-rolls $C C'$, and the distance between the two bights gradually increases. These tapes or strings serve for conducting the moistened sheet onto a delivery-table B' , that is supported in horizontal position by means of braces B^2 , which are hinged to the under side of the table B' and supported by their forked lower ends y on a transverse rod r of the main frame, as shown in Fig. 1. The inner end of the table B' is hinged at b' to the standard A^3 and may be dropped on the release of the braces B^2 into vertical position alongside of the end of the main frame A , so as to take up less room when the machine is packed for shipment or when the same is not in use.

One of the moisture-applying rolls D and the transmitting-roll C^2 are provided with scrapers E , carried by spindles X , journaled in horizontally-projecting lugs e of the standards A^2 , as shown in Figs. 3 and 4, said scrapers serving for uniformly distributing the moisture transmitted from the roll D to the transmitting-roll C^2 and from the latter to the lower dampening-roll C' . The scrapers E are pressed, by means of springs t , against the rolls D and C^2 , as shown in Figs. 3 and 4, so as to increase the efficiency of the scraping action. The lower scraper extends across the entire width of the moistening-roll D , while the upper scraper extends only over the ends of the transmitting-roll C^2 , as shown in Fig. 5, so as to remove the surplus moisture from the roll C^2 at both sides of the sheet and protect thereby the edges of the sheets to be dampened from an oversupply of moisture. These scrapers E are preferably made in sections, so that the end sections can be placed in use while the intermediate sections are removed, or all the sections can be arranged in contact with the transmitting-roll D , as desired.

Motion is transmitted to the machine from a driving-shaft S , which is supported in bearings of a bracket-arm A^4 and of the adjacent standard A^2 , the driving-shaft being provided with the usual fast and loose pulleys $P P'$ and a belt-shifting device H , said belt-shifting device being operated by a rod h , guided in ears h' of the main frame and provided with a handle h^2 at the opposite end, so that the belt can be readily transferred from the loose to the fast pulley, and vice versa, whenever the machine is to be set to motion or stopped. Motion is transmitted from the driving-shaft S by suitable transmitting-gears to the intermediate transmitting-roll C^2 and the dampening-rolls $C' C$, as shown in Figs. 1 and 2, while the moisture-supplying rolls are rotated by frictional contact with the transmitting-roll

C^2 . The transmitting-roll C^2 and the dampening-rolls C' and C are covered by felt-cloth or other moisture-absorbing fabric, so that the uniform degree of moisture is supplied to the sheets passed through between the dampening-rolls, so that they are ready for immediate use in a lithographic or other printing press. On the driving-shaft S is placed a sleeve i , which carries a smaller and a larger pinion i^2 , said sleeve being capable of being shifted on the driving-shaft S , so that the pinion i^2 is either placed in line with gear-wheel on the shaft of the transmitting-roll or the pinion i^2 in line with an auxiliary gear i^3 on the shaft of the transmitting-roll C^2 , so that two different speeds can be imparted by the gears to the transmitting and dampening rolls, according to the degree of moisture to be transmitted to the sheets by the dampening-rolls.

My improved machine for dampening sheets for commercial lithographing and printing work has the advantage that the sheets can be dampened with the required degree of moisture without being passed bodily through a fountain, so as to be ready for use in the press in a much less time than when the sheets are passed through a fountain. Further, the sheets are moistened uniformly, so as to be ready for printing without requiring the draining off of the surplus water, whereby considerable time is saved and more satisfactory work produced.

Having thus described my invention, I claim as new and desire to secure by Letters Patent—

1. In a machine for dampening sheets, coöperating dampening-rolls, a transmitting-roll, oppositely-disposed supplying-rolls rotatable in contact with the latter, scrapers engaging and extending throughout the length of one of said supplying-rolls, and scrapers engaging the end portions only of said transmitting-roll.

2. In a machine for dampening sheets, coöperating dampening-rolls, a transmitting-roll, supplying-rolls rotatable in contact with the latter, a set of scrapers engaging and extending throughout the length of one of said supplying-rolls, and a second set engaging the end portions only of said transmitting-roll, the scrapers in said sets being oppositely disposed.

3. In a machine for dampening sheets, the combination, with the dampening-rolls and the transmitting-roll, of oppositely-disposed supplying-rolls rotatable in contact with the latter, depending scrapers engaging and extending throughout the length of one of said supplying-rolls, and upwardly-extending scrapers disposed at the opposite side of said transmitting-roll and engaging the end portions only thereof.

4. In a machine for dampening sheets, a suitable support, coöperating dampening-rolls and a transmitting-roll rotatable in said sup-

port, supplying-rolls rotatable in contact with said transmitting-roll, oppositely-disposed spindles contiguous and parallel to the latter, and spring-pressed scrapers carried by said 5 spindles, the scrapers on one of said spindles contacting with one of said supplying-rolls, while the scrapers carried by the opposite spindle contact with said transmitting-roll.

In testimony that I claim the foregoing as my invention I have signed my name in presence of two subscribing witnesses. 10

ALEXANDER B. SHERWOOD.
